UNITED STATES PATENT OFFICE

165,042

CREAMER

Eva S. Zeisel, New York, N. Y., assignor to United China and Glass Co., New Orleans, La., a corporation of Louisiana

Application July 12, 1950, Serial No. 11,105

Term of patent 14 years

(Cl. D44—21)

To all whom it may concern:

Be it known that I, Eva S. Zeisel, a citizen of the United States, residing at 431 Riverside Drive, New York, county of New York, and State of New York, have invented a new, original, and ornamental Design for a Creamer, of which the following is a specification, reference being had to the accompanying drawing, forming a part hereof.

Fig. 1 is a side elevational view of a creamer showing my new design;

Fig. 2 is a top plan view; and

Fig. 3 is a horizontal sectional view substantially on line 3—3 of Fig. 1.

I claim:

The ornamental design for a creamer, as shown.

EVA S. ZEISEL.
